UNITED STATES PATENT OFFICE.

ARCHER F. DUGUID, OF MONTREAL, QUEBEC, CANADA.

PLUMB-BOB.

1,212,194.

Specification of Letters Patent. Patented Jan. 16, 1917.

Application filed July 28, 1913. Serial No. 781,598.

To all whom it may concern:

Be it known that I, ARCHER F. DUGUID, a subject of the King of Great Britain, and resident of the city of Montreal, in the 5 Province of Quebec and Dominion of Canada, have invented certain new and useful Improvements in Plumb-Bobs, of which the following is a full, clear, and exact description.

10 This invention relates to improvements in plumb-bobs for use in connection with various kinds of survey work, but is particularly adaptable for underground work.

15 The object of the invention is to provide a plumb-bob by means of which the desired vertical line may be more accurately determined than is at present possible.

20 The invention is based on the principle that it is much easier to accurately bisect the image of a bright area (symmetrical about its major axis) with the vertical hair of a transit than to set the hair accurately on a plumb-bob string or other dark object. The means used to put this principle into practice 25 consists of a plumb-bob having slots formed therethrough at various angles, so that however the plumb-bob turns light will always be visible through at least one of the slots.

30 In the drawings which illustrate the invention:—Figure 1 is a perspective view of the device. Fig. 2 is a vertical sectional view. Fig. 3 is a plan view. Figs. 4 and 5 are partial elevations showing slightly alternative forms.

35 Referring more particularly to the drawings, 6 designates the cylindrical body of a plumb-bob which may be either tubular, as shown in Figs. 1 and 2, or solid, as shown 40 in Figs. 4 and 5. In either case, the top and bottom of the body are weighted, the bottom weight being naturally greater. The top 7 is provided with an accurately centered aperture 8 for the attachment of a cord 9, while 45 the lower end 10 is conically formed, the apex 11 of the cone being located exactly in the axis of the body. This axis is designated by the numeral 12. In the form shown in Figs. 1 and 2, the body portion is tubular, as 50 previously stated, and the top 7 and bottom 8 are secured thereto by screw threads or other suitable means, as clearly shown in Fig. 2. A number of diametrically arranged slots 13 are formed through the body one be- 55 low the other, and in staggered relation:

These slots are preferably of such width that no matter how the device is rotated around its axis, light will be visible through at least two of the slots. Of course if the slots are made narrower, it will be possible to arrange the plumb-bob so that light is visible through only one. These slots are 60 symmetrically arranged on opposite sides of vertical planes, passing through diameters of the body. It is therefore obvious that however the plumb-bob is turned about its axis, the vertical line bisecting the area of light silhouetted by the body will coincide 65 with the vertical axis of the plumb-bob. It will also be seen that a horizontal line bisecting any of the slots will also coincide with the vertical axis of the plumb-bob. The slots 70 may be rectangular, rhomboidal, elliptical or any other suitable shape. In fact, many of these shapes will prove more satisfactory in 75 use than the plain rectangles, as it will be much easier to determine the bisecting line. In use, for example, in mines, the plumb-bob is hung in the desired position and an illuminated screen placed behind same. The surveyor then makes his sight and sets his instrument, so that the vertical hair exactly bisects the area of light inclosed by the dark 80 body, as seen in the silhouette. This operation may be performed much more accurately than would be possible if the stadia hair were sighted on the plumb-bob string.

85 While the device has been shown provided with only four apertures, it is obvious that any suitable number may be used and placed 90 at equal angles apart. In outdoor work, the inclosed areas of light would not be so easily visible as in mine work, and in this class of work, it may be found advisable to use a light colored plumb-bob on which dark ribbons are wound. The bob may if necessary 95 be transparent. It is obvious that such minor changes may be made to adapt the device to various classes of work without departing from the spirit of the invention.

100 Having thus described my invention, what I claim is:—

1. A cylindrical plumb-bob having a plurality of diametric slots formed therethrough in staggered relation one to the other, said 105 slots being each symmetrical on opposite sides of a vertical plane passing through a diameter of the bob.

2. A cylindrical plumb-bob having a plurality of diametric slots formed there- 110

through, one above the other, said slots being of such size and arrangement that there is always a clear view through one of said slots, the view opening being symmetrically arranged on opposite sides of an imaginary line passing through the axis of the bob.

In witness whereof I have hereunto set my hand in the presence of two witnesses.

ARCHER F. DUGUID.
